(57) **CLAIM**

The ornamental design for the apparatus for holographic video conferencing, as shown and described.

DESCRIPTION

FIG. 1 is a top perspective view of the invention.

FIG. 2 is a bottom perspective view of the invention.

FIG. 3 is a top plan view of the invention.

FIG. 4 is a bottom plan view of the invention.

FIG. 5 is a left side view of the invention with the retractable camera lens extended.

FIG. 6 is a right side view of the invention.

FIG. 7 is a front perspective view of the invention with the retractable camera lens in the extended position.

FIG. 8 is a rear perspective view of the invention.

FIG. 9 is a top plan view of the invention with the camera window and the keyboard window partially open.

FIG. 10 is a top perspective view of the invention with the camera window and the keyboard window partially open.

FIG. 11 is front perspective view of the invention in use with the camera window and the keyboard window fully open.

FIG. 12 is rear perspective view of the invention in use with a projector screen; and,

FIG. 13 is front perspective view of the invention in use with a projector screen.

The dotted lines in FIGS. 2, 8–13 are for illustrative purposes only showing environment, forming no part of the claimed design.
